UNITED STATES PATENT OFFICE.

HANS HANSON, OF HARTFORD, CONNECTICUT, ASSIGNEE, BY MESNE ASSIGNMENTS, TO
UNDERWOOD COMPUTING MACHINE COMPANY, OF NEW YORK, N. Y., A CORPORA-
TION OF NEW YORK.

COMBINED TYPE-WRITING AND COMPUTING MACHINE.

1,226,970.

Specification of Letters Patent. Patented May 22, 1917.

Application filed September 25, 1912. Serial No. 722,223.

To all whom it may concern:

Be it known that I, HANS HANSON, a citizen of the United States, residing in Hartford, in the county of Hartford and State 5 of Connecticut, have invented certain new and useful Improvements in Combined Type-Writing and Computing Machines, of which the following is a specification.

This invention relates to computing machines, and is herein illustrated as applied to a combined typewriting and computing machine of the Underwood Hanson type in which a series of jacks are successively moved by a tappet on the typewriter carriage so as to act as denominational selectors in a manner determined by the movement of said typewriter carriage.

In said Underwood Hanson machines, as herein illustrated, each jack is arranged to cause one of a series of computation racks to be moved into position where its pin may be set by means of the numeral key of the typewriter then depressed. The computation racks and the computing mechanism connected thereto may be of any desired form. A series of these jacks is shown as arranged in a frame fastened to brackets on the main frame of the typewriter, and a tappet fast on the typewriter carriage is arranged to pass adjacent to said jacks and to raise them *seriatim* as the typewriter carriage is fed along by the operation of the typewriter keys. The frame holding these jacks preferably comprises a unitary box member having a rod extending across it, on which rod the jacks are pivoted, and in the front end of said frame there is preferably cut a series of teeth which guide the front ends of said jacks. The rear ends of said jacks are preferably guided by a comb which is removably attached to the rear end of said frame, and the bar of the frame on which said comb rests may be arranged to limit the throw of said jacks. Preferably on the rear end of said bar are cut a series of segmental guides, in which rods extending from said jacks to the computing mechanism proper are arranged to be held, and by which guides they are guided. A bail, pivoted on the frame holding the jacks, may be arranged to extend around said rods and hold them in position so that each rod will be held under its jack, and said bail may be provided with a latch to hold it in position. For limiting

the throw downward of said jacks in front, 55 there may be an adjustable cross rod which may be locked at any desired position. The sides of the frame which holds these jacks may extend upward at the top and be slightly undercut so that a cover may slide 60 in and be held by said undercuts. The box frame preferably includes lugs which are arranged to embrace a cross bar fast on the frame of the typewriting machine and through these lugs screws may be passed 65 which serve to lock said frame in any desired position on said cross bar.

Other features and advantages will hereinafter appear.

In the accompanying drawings, 70 Figure 1 represents a side view largely diagrammatic of an Underwood Hanson computing machine to which my invention is applied.

Fig. 2 is a perspective view of the frame 75 and some other parts showing my invention.

Fig. 3 is a longitudinal section through the frame.

Fig. 4 is a transverse section through the same. 80

Numerical keys 1 on key-levers 2 are depressed to swing type-bars 3 by means of bell-crank 4 upwardly and rearwardly against a platen 5 so that type 6 print thereon. Said platen is rotatably mounted in a 85 carriage 5^a and drawn forward in letter feeding direction by a spring not shown, and is controlled in said feeding by means of an escapement wheel 7 carrying a ratchet wheel 8 which works in a rack 9 on said carriage. 90 Said escapement wheel is controlled by dogs 10 operated through the universal bar 11 by means of heels 12 on the type bars. As said carriage 5^a is fed forward, a tappet 13 fast on a bracket 14 on said carriage is arranged 95 to successively strike and lift jacks 15 pivoted on a universal axis formed by a cross bar 16 so that by means of rods 17 computation bars 18 are successively brought into operative position being swung upward by 100 means of levers 19. When a computation bar 18 is thus swung upward, it raises pins 20 on it into position to be struck by linkages 21, which linkages are operated by rock arms 22 fast on rock shafts 23, so that when a key 1 24 is depressed a stem 24 on said key will swing rock shaft 23 by means of a rock arm 25 and depresses the lower reach of its cor-

responding linkage 21. It will be seen there is one such linkage for each numeral key. When a pin 20 has thus been set, as above described, the lower end of it will project below the computation bar 18 so that it lies in the path of the cross bar 26 forming part of a general operator. After a number composed of the desired digits has been thus recorded by setting pins, the general operator is carried forward by means of a segment wheel 27 so that the numbers represented by pins set are recorded in computing wheels 28 which carry gears 29 meshing with racks 30 on the computation racks 18. All the above parts are substantially those known in the art, and are shown in the British Patent No. 3390 of 1912.

The jacks 15 in the present invention are mounted in a box frame 31 which may be a four-sided unit in which the rod 16, on which said jacks are pivoted, is mounted. Said jacks 15 are preferably held apart without the use of washers or other spacing devices on said rod, by means of teeth 32 cut in the front member of said frame, and at the rear end of said frame by means of a comb 32^b having teeth 33 between which said jacks 15 may play. Said comb rests on the rear member 34 of said frame and may be held to said frame by screws 32^a. The jacks 15 preferably extend beyond said comb some distance, so that they rest on the tops of the rods 17, and said rods are held in position by means of segmental teeth 35 cut on the rear side of said member 34. Said rods 17 may be held in place against said segmental teeth by means of a bail 36 pivoted on the outside of said frame by the screws 36^a which hold the rod 16. This bail may be swung up out of the way, but is normally held in place to hold said rods by means of a spring latch 37 arranged to engage an extension 38 on said frame. The rear member 34 may serve to limit the throw of the jacks 15 downward in the rear, and the throw downward in front of said jacks is preferably adjustably limited by means of a flattened bar 39 placed adjacent the lower edge of said jacks and arranged to be locked by means of nuts 40 so that its edge may be placed at a varying distance from said jacks and thus vary their throw. Said frame 31 preferably has extending partly across its bottom a floor 41 which is channeled to accommodate a fixed rod 42 on the main frame of the typewriter and lugs 43 and 44 on the ends of said frame arranged to partly embrace said bar 42 and accommodate a screw 45 which will lock the frame in position on said bar. The end portions 46 of the frame 31 may be extended upward and slightly under-cut as seen at 47 so as to accommodate a sliding cover 48 which is arranged to extend over the front end and over the comb 32. Said cover may be locked in position by means of a screw 49 having a

head which enters a cut-away portion 50 in said cover, said screw taking into the side of said frame.

Variations may be resorted to within the scope of the invention, and portions of the improvements may be used without others.

Having thus described my invention, I claim.

1. In a computing machine, the combination with a series of jacks and denominational selecting rods operated thereby, of a frame in which said jacks are pivoted, guides on the end of the frame for said rods, and a comb forming guides for said jacks adjacent said rod guides.

2. The combination with a series of jacks pivotally mounted to vibrate about an axis, of means for vibrating said jacks, and guiding means engaging the ends of said jacks which are engaged by said vibrating means adapted to confine the movement of said jacks to their normal direction of vibration about their axis.

3. The combination with a series of jacks pivotally mounted to vibrate about an axis, of means for vibrating said jacks, a series of rods, one for each of said jacks, said jacks contacting freely with their accordant rods, guiding means for said rods, guiding means for said jacks to hold them to their planes of vibration, and guiding means for the ends of said jacks contacting with said rods, said last-mentioned guiding means corresponding with the guiding means for said rods so as to maintain said jacks in register with said rods.

4. The combination with a series of pivotally-mounted jacks adapted to vibrate about a common axis, of means to vibrate said jacks, a series of rods arranged to be actuated by said jacks, there being one of said rods for each of said jacks, said rods and said jacks contacting freely, guiding means engaging the ends of said jacks which are engaged by said vibrating means so as to hold said jacks against movement transverse to the plane of vibration of said jacks by said vibrating means when said vibrating means engages said jacks, guiding means for said rods, and guiding means for the ends of said jacks engaging said rods, said last-mentioned guiding means and the guiding means for said rods being dentated and corresponding one with the other, so that the ends of said jacks contacting with said rods will always be maintained in register with said rods.

5. The combination with a series of pivotally-mounted jacks adapted to vibrate about a common axis, of means to vibrate said jacks, a series of rods arranged to be actuated by said jacks, there being one of said rods for each of said jacks, said rods and said jacks contacting freely, guiding means engaging the ends of said jacks

which are engaged by said vibrating means so as to hold said jacks against movement transverse to the plane of vibration of said jacks by said vibrating means when 5 said vibrating means engages said jacks, guiding means for said rods, guiding means for the ends of said jacks engaging said rods, said last-mentioned guiding means and the guiding means for said rods being 10 dentated and corresponding one with the other so that the ends of said jacks contacting with said rods will always be maintained in register with said rods, and means for limiting the pivotal movements of said 15 jacks.

6. The combination with a series of pivotally-mounted jacks adapted to vibrate about a common axis, of means to vibrate said jacks, a series of rods arranged to be 20 actuated by said jacks, there being one of said rods for each of said jacks, said rods and said jacks contacting freely, guiding means engaging the ends of said jacks which are engaged by said vibrating means 25 so as to hold said jacks against movement transverse to the plane of vibration of said jacks by said vibrating means when said vibrating means engages said jacks, guiding means for said rods, guiding means for 30 the ends of said jacks engaging said rods, said last-mentioned guiding means and the guiding means for said rods being dentated and corresponding one with the other so that the ends of said jacks contacting with 35 said rods will always be maintained in register with said rods, and means for limiting the pivotal movements of said jacks, said last-mentioned means being adjustable so that the pivotal swing of said jacks may be 40 varied:

7. The combination with a series of jacks, of a mounting for said jacks enabling a movement thereof, means for actuating said jacks, and limiting means for determining 45 the extent of movement of said jacks, said limiting means being adjustable so as to vary the throw of said jacks.

8. In a machine of the character described, a series of jacks pivotally mounted 50 on a common axis, means for vibrating said jacks, said jacks normally projecting across the path of movement of said means, and adjustable means for varying the extent of 55 projection of said jacks across the path of movement of said vibrating means.

9. In a machine of the character described, a series of jacks, means for moving 60 said jacks, and means universal to all of said jacks for determining the relative position of said jacks with respect to said moving means, said determining means being adjustable so as to vary the relative position of said jacks with respect to said moving means.

65 10. The combination with a pivot rod

forming a universal axis, of a series of jacks freely pivoted on said rod with clear spaces therebetween at their points of pivot, guiding means universal to all of said jacks engaging the same at both ends thereof so as to prevent movements of said jacks at either end transverse to their planes of swing, and means for vibrating said jacks in said guiding means so that they swing upwardly at one end and downwardly at the other in planes determined by said guiding means.

11. The combination with a frame, of a series of jacks mounted in said frame, a series of rods contacting with said jacks to be actuated thereby, a bail for maintaining said rods in contact with said jacks, an extension on said frame, and a spring lock on said bail engaging said extension to hold said bail in position.

12. The combination with a series of jacks, of an inclosing and supporting frame for said jacks, said jacks abutting at one end against one side of said frame and extending at their other end through passages at the opposite sides of said frame, one of said sides being detachable so as to permit the insertion of said jacks in position in said frame.

13. The combination with a frame, of a series of jacks mounted in said frame, and a comb open at one side straddling said jacks and detachably abutting at its open side against said frame so as to form inclosing passages through which said jacks project outwardly from said frame.

14. The combination with a frame, of a series of jacks pivotally mounted in said frame, and a rod having a bearing edge universal to and engaging said jacks to limit the movement thereof, said rod being adjustable to vary the position of said bearing edge with respect to said jacks so as to vary the limit of movement of said jacks.

15. The combination with a frame, of a series of jacks pivotally mounted in said frame, and a rod having a bearing edge universal to and engaging said jacks to limit the movement thereof, said rod being rotatably mounted so as to vary the elevation of said bearing edge and thus vary the limit of movement of said jacks.

16. The combination with a series of jacks and a series of rods which they actuate, of moving means for actuating said jacks and a casing for said jacks inclosing the same on all sides, said casing having an opening at the front of the bottom to permit the engagement of said jacks by said moving means and having a series of passages in one end through which said jacks extend to engage said rods.

17. The combination with a series of jacks, of moving means for actuating said jacks, a series of rods, one universal to each of said jacks, engaging said jacks to be actu-

ated thereby, and a casing inclosing said jacks and having four sides and a top and bottom, said casing being open at one end of the bottom to permit said moving means to have access to said jacks, and said casing also having guiding passages therethrough through which said jacks extend to engage said rods.

18. The combination with a series of jacks arranged to be subjected to a stress transverse to the planes of their movement and to effect a thrust in the planes of their movement, of a rod common to said jacks on which said jacks are freely mounted as

regards a sliding movement along said rod 15 and constrained for a pivotal movement about said rod, and guiding means located both fore and aft of the pivotal axis of said jacks about said rod, so as to prevent transverse movements of said jacks along said rod 26 when subjected to said transverse strain, and so as to insure a positive direct thrust in the planes of movement of said jacks.

HANS HANSON.
